UNITED STATES PATENT OFFICE.

LEON A. ALTSCHUL, OF DAYTON, OHIO.

DISPLAY RACK.

Application filed April 12, 1926. Serial No. 101,306.

This invention relates to display racks, it more particularly relating to display racks for women's hosiery.

The object of my invention is to provide a display rack of a simple character by which women's hosiery may be displayed in a manner to prevent displacement of the hosiery during the process of examination by the customers but at the same time enable the customers to freely handle certain portions of the hosiery, if desired.

A further object of my invention is to provide a simple display rack of comparatively small dimensions, but on which a large number of hose may be displayed; a further and more specific object of the invention in this connection being to provide for securing the hosiery upon the rack in overlapping relation, leaving a small portion only of each hose exposed for observation, but at the same time allow for the free handling by the customers of the upper portions of the hosiery.

In the accompanying drawings:

25 Fig. 1 is a front elevation of a display rack embodying my improvements, the major portion of the rack in this figure being constructed of wood.

Fig. 2 is a section on the line 2—2 of Fig. 1.

Fig. 3 is an elevation of the portion of the rear side of the rack.

Fig. 4 is a section on the line 4—4 of Fig. 3.

35 Fig. 5 is an enlarged view of a small portion of the forward side of the rack.

Fig. 6 is a front elevation of a modified form of rack shown constructed of metal.

Fig. 7 is a side elevation of the rack shown in Fig. 6.

Fig. 8 is a vertical section on the line 8—8 of Fig. 6.

Fig. 9 is a section on the line 19—19 of Fig. 6.

45 Fig. 10 is a rear view of a portion of the modified form of rack.

Referring particularly to Figs. 1 to 5 of the drawings, 1 represents a wooden frame of rectangular shape to which is fitted and secured in a suitable way a panel 2 and a strip 3. The panel 2 covers the entire area of the frame excepting the upper portion thereof and the strip 3 extends transversely across the extreme upper portion of the frame leaving a space or slot 4 between the upper edge of the panel and the lower edge

of the strip. The frame is designed to be supported in an inclined position as shown in Fig. 2 by a pair of supports 5 and 5', one of these supports being shown in full lines in Fig. 2 and both supports in dotted lines in Fig. 1. These supports 5 and 5' are hinged to the frame by the hinges 6 so as to swing inwardly towards the rear side of the panel 2 for transportation purposes or be swung out to a position at right-angles to said panel to support the rack.

On the forward side of the rack is a clamping bar 7, preferably made of a metal rod, round in cross-section, the ends of which are journaled in transversely-extending apertures 8 in the side pieces of the frame and one end of which is bent at right-angles as indicated at 7^a to form a handle or crank by which the clamping rod may be turned. As indicated in dotted lines in Fig. 1 and also shown in Fig. 4, this rod 7, immediately adjacent the side frame pieces, is bent or offset at the points indicated at 7^b so that when the rod is in the dotted line position of Fig. 1 there is a space between the rod and the back 2, but when the rod is turned to the full line position of Fig. 1 that portion of the rod between the bends 7^b will tightly hug the front surface of the panel 2. 80 The panel 2 is preferably provided with a pair of short transversely-extending grooves 9 which lie immediately beneath the ends of the rod 7, when it is turned to a clamping position, to eliminate any undue binding of the rod at those points. This clamping bar is arranged substantially midway the height of the rack.

On the rear side of the rack there is a second clamping bar 10, preferably of wood. 95 One end of this bar 10 is inserted in a recess 11 formed on the inner side of the support 5 and the outer end of the bar is placed in a long tapered recess 12 formed on the inner side of the outer support 5', and this end of the bar forced down the inclined wall of this recess until the bar stands in horizontal position, in which position the inner edge thereof will more or less tightly hug the rear side of the panel 2 and the bar will also act to brace the supports 5 and 5' to keep them from swinging inwardly upon their hinges.

In operation the stockings are inserted through the slot 4 and hung upon the upper 110 edge of the panel 2, with the feet hanging downwardly on the rear or unexposed side

of the panel and the upper portion of the stockings hanging downwardly on the forward or display side of the rack. The stockings are placed in overlapping relation as indicated at 13, the degree of overlap depending upon the number of stockings which it is desired to display. The clamping bar 10 is then inserted in position so as to clamp the feet of the stockings, as shown in Fig. 3, at 10 the same time spread and hold the supports 5 and 5'. When the stockings are inserted upon the rack, the clamping bar 7 will be turned to the position shown in dotted lines in Fig. 1, but after the stockings have been 15 properly positioned this rod is turned by the handle 7^a to the full line position so as to act with a cam effect to firmly clamp the stockings to the forward side of the panel 2, leaving the extreme upper ends of the stockings, however, free to be handled by the 20 customers. Cards 16 bearing the name of the shades or colors of the hosiery are inserted in the channel 14 in registry with the stockings so that the customer may readily select 25 the shade of the hosiery desired. Preferably, there is supported on the upper part of the frame a hood 15 for an electric light, the hood 15 being open on its under side so that the light is reflected on the hosiery.

30 Referring now to Figs. 6 and 10, there is illustrated another embodiment of my invention showing the rack constructed of metal in which 17 represents side frame members, either of flat or channel form, to 35 which are secured a metallic panel 18 of sheet metal and an upper transverse strip 19, also of sheet metal, the lower edge of which is spaced away from the upper edge of the panel 18 to provide a slot through 40 which the hosiery is inserted when placing the same upon the rack in the manner described in connection with my other instruction. Metallic strips 21 are pivoted at their upper ends to the side frame 17 and also 45 have pivotally connected to their lower ends brace rods 22 which extend to and are pivotally connected to the side frame, these strips 21 forming supports for the rack when in the position shown, and to permit the 50 supports 21 and legs 22 to be folded for transportation purposes, the pivotal connection between the same is in the form of a bolt 23 extending through apertures in the parts 21 and 22 and held from displacement 55 by a wing-nut 24 which can be readily removed when it is desired to fold the rack.

As in my other construction described there are employed two clamping bars, one on the front and one on the rear of the back 60 18. The front clamping bar, indicated at 25, is in the form of a bent rod mounted in apertures in the side frame members 17 and having an operating handle 25^a formed by bending one end at right angles, this rod 25 being bent as indicated in dotted lines in

Fig. 9 so as to give the desired clamping effect described in connection with the clamping bar 7. The rear clamping bar is shown at 26 and is preferably a flat metallic bar which is pressed downwardly into clips 27 70 secured to the rear sides of the supports 17 so as to clamp the feet of the hosiery. The rear clamping bar may, however, be made the same as the front bar, if desired. The manner of inserting the hosiery upon the 75 rack and displaying the same is the same as in connection with my other construction.

By this arrangement it will be seen that a very simple and inexpensive rack is provided for the display of hosiery, the construction 80 being such that a great many hose may be displayed by a rack of small dimensions and in a manner to firmly hold the hosiery in position, but at the same time afford ample facilities for examination by the customer. 85

While I have shown and described the stockings so disposed on the rack that the feet hang on the rear of the rack and the upper portions of the stockings on the front thereof, yet this arrangement can be reversed with equally good results as to the display of the stockings; that is, the feet of the stockings can hang downwardly on the front of the rack with the feet portions left free for examination by the customers. 90

Having thus described my invention, I claim:

1. In a display rack, a frame, foldable means hinged to the frame for supporting said frame in an inclined position, a panel secured in said frame with space above the upper edge of said panel so that the upper edge of said panel affords means for suspending a plurality of fabric articles therefrom with portions of the articles hanging respectively on the display side and unexposed side of said panel, means for securing the hanging ends of said articles on the unexposed side of said rack and means for securing the hanging portions of said articles on the forward side of said panel at a point removed from the ends of said articles so that the ends of the articles on the display side of the rack will be left free for inspection. 115

2. In a display rack, a frame, foldable means hinged to the frame for supporting said frame in an inclined position, a panel mounted in said frame having a horizontal edge at its upper end affording means for suspending stockings in overlapping relation with portions thereof on the display side of said panel and portions on the unexposed side, means for clamping the hanging portions of said stocking to the unexposed side of said panel, and means for clamping the outer portions of said stockings to the display side of said support at a point removed from their ends so that a substantial portion of said stockings will be left free for 120 125 130

inspection on the display side of said rack.

3. In a display rack, a panel having a horizontal upper edge for suspending a plurality of stockings in overlapping relation from an intermediate point of said stockings, means for supporting said panel in an inclined position, a clamping bar on the rear side of said panel for clamping the hanging ends of said stockings, and a second clamping bar on the display side of said panel to clamp the hanging ends of said stockings,¹⁵

said second bar consisting of a bar rotatably mounted at the sides of said panel and having that portion thereof coinciding with the panel offset so that the rotation thereof will cause the offset portion to act as a cam to clamp the stockings to the display side of said panel.

In testimony whereof, I have hereunto set my hand this 8th day of April, 1926. ²⁰

LEON A. ALTSCHUL.
